UNITED STATES PATENT OFFICE.

FRED RICKS AND REGINALD BOYD WOODCOCK, OF LEICESTER, ENGLAND, ASSIGNORS
TO UNITED SHOE MACHINERY CORPORATION, OF PATERSON, NEW JERSEY, A COR-
PORATION OF NEW JERSEY.

LASTING AND SEWING MACHINE.

Application filed December 1, 1921. Serial No. 519,162.

To all whom it may concern:

Be it known that we, FRED RICKS and REGINALD BOYD WOODCOCK, subjects of the King of England, residing at Leicester, Leicestershire, England, have invented certain Improvements in Lasting and Sewing Machines, of which the following description, in connection with the accompanying drawings, is a specification, like reference characters on the drawings indicating like parts in the several figures.

This invention relates to machines for operating on shoes. The invention is herein set forth in its application to a machine for lasting and sewing stitchdown shoes of the type disclosed in United States Letters Patent No. 1,321,148, granted November 11, 1919, on application of one of the present applicants, Fred Ricks. This machine comprises lockstitching instrumentalities, an upper stretching gripper operating in timed relation to said instrumentalities, shoe positioning means to grip the margin of the sole, and other means hereinafter referred to as auxiliary positioning means to engage the shoe bottom farther from the operating point.

In the use of a machine of this type we have observed that while it is convenient to cause the auxiliary positioning means, when in action, to move to and from the shoe bottom so as to rise clear from the shoe bottom in each cycle of operations, and thus give the operator freedom to manipulate the shoe and avoid constraint on the feed, it is nevertheless desirable that the said means should move only a short distance from the shoe bottom, since if the movement is much it becomes possible for the operator to tilt the shoe considerably upward which adds unnecessarily to the corrective action called for from the positioning means and, having regard to the short time available, tends to cause the said positioning means to act in a relatively violent manner on the shoe with consequent liability to discomfort to the operator and displacement of the work.

The highest position to which it is desirable to raise the auxiliary positioning means when in action is, however, such that if said means occupies that position when it is out of operation it is apt to constitute a distinct obstruction when stitching is be-

ing performed in the shank of the shoe, a part of the shoe which customarily does not require the use of the auxiliary positioning means but which, owing to its shape and proportions, does usually require that the operator shall have considerable latitude for tipping the shoe in the course of stitching. It is an object of the invention to provide auxiliary positioning means which will conform fully with these requirements.

In machines of the type in question it is customary to provide a knee lever control for putting the gripper into or out of action and for varying the pulling action thereof such as is disclosed in British Patent No. 22110 of 1913. The provision of an additional manual controller for the auxiliary positioning means as aforesaid imposes, we have found, an inconvenient additional burden upon the operator already busied with control of the operation of the machine by the customary clutch treadle and the knee-lever as aforesaid.

We have, however, ascertained that the operator requires either that the gripper be acting with a relatively limited pulling action with the auxiliary positioning means out of action (a condition of affairs prevailing when stitching the sides of the shoe at the shank) or that he requires the auxiliary positioning means to be in action with the gripper mechanism giving either the limited pull referred to or a more extended pull, and it is accordingly a further object of this invention to take advantage of these ascertained requisites in operation to reduce the number of controls calling for the operator's attention during operation on a shoe when the machine is equipped with means both to control the pull of the gripper and to control the auxiliary positioning means.

Again we have found that the path of operative movement of auxiliary positioning means which moves to and from the shoe when in operation frequently requires to be displaced without varying the extent of its movement, and it is a further object of the invention to provide ready means for securing this result.

With the above and other objects in view, one important feature of the invention consists in auxiliary positioning means movable, when in operation, toward and from

the shoe in time relation to the operation of the machine and means arranged for operation during work upon a shoe to move said positioning means into an inoperative position, said position being farther from the shoe than the most remote position which the said positioning means assumes when in operation.

Another feature of the invention comprises, in a machine of the type referred to, a unitary control for the gripper and auxiliary positioning means to control these devices relatively to the stitching instrumentalities.

Still another feature of the invention consists in means arranged for convenient adjustment by the operator during operation of the machine for varying the initial position of the positioning means without affecting the extent of its operative movement. Preferably and as disclosed, means is provided for indicating audibly the amount of adjustment being produced.

The above and other objects and features of the invention will become fully evident to those skilled in the art from a consideration of a preferred construction according to the invention, which is applied to a machine as described in the above mentioned patents and the novel parts of which are shown in the accompanying drawings in which,

Fig. 1 is a side elevation, partly in section, of a machine having embodied therein the present invention;

Fig. 2 is a side elevation of the mechanism for operating the auxiliary positioning means taken from the side opposite to that of Fig. 1; and

Figs. 3 and 4 are details of mechanism shown in Fig. 1.

The machine in general organization is similar to that disclosed in the patents above mentioned comprising a work rest 1 arranged to enter the angle between the side of the last and the projecting sole margin of an inverted stitch-down shoe. The upper of the shoe lies against the rest 1 and the margin of the upper which projects beyond the sole is seized by a gripper 3 and tensioned outwardly, the movement of the gripper being effected by a lever 5 operated by a cam 7 on a shaft 9. The sewing mechanism by which the upper and sole are secured together in the angle between the side of the shoe and the outturned flange of upper comprises the usual presserfoot and curved awl and needle mechanism similar to that disclosed in United States Letters Patent No. 473,870 granted April 26, 1892, on application of French and Meyer.

The auxiliary positioning means 2 is fast on an arm 4 of a bell crank lever pivoted at 5 to the machine frame. The other arm 6 of the lever is forked to receive the end of a link 8 connected thereto by a pivot pin 10

having an eccentric portion 12, an adjusting finger piece 14 fast to it, and a head 16. The head 16 has a series of peripheral recesses into any one of which a spring-pressed plunger 18 may snap as the pin is rotated by the finger piece 14. The plunger 15 is housed in the lever 6 and locks the head 16 in adjusted position, there being pins 20 in the head the ends of which project from the head to act as means to limit, by engagement with the lever, the rotation of the head in either direction. By rotating the eccentric portion 12 by means of the finger piece 14 the operator can immediately adjust the active position of the auxiliary positioning means 2 about the pivot 5 of the lever without varying the extent of its movement, and the clicking engagement of the plunger with the recesses acts audibly to indicate to him what amount of adjustment he is producing.

The rear end of the link 8 is pivoted at 21 to the upper end of a lever 22 pivoted at 24 to an arm 25 formed on the upper side of the hub of a lever 27 which constitutes part of the thread measuring mechanism of the sewing machine which is similar to that disclosed in the above mentioned Patent No. 473,870, the lever 27 having a rocking movement on a shaft 29. Between its ends the lever 22 has pivoted to it at 23 a latch bar 26 urged downwardly by a spring 28 connected at its ends to the bar and to a bracket 30 secured to the frame. Pivoted to the bracket at 32 is a lever 34 having a cam end 35 against which a cam roll 36 on the pivot 21 at the upper end of the lever 22 is held by a spring 38 connecting the pivot 21 with the bracket 30. The lever 34 has pivoted to it the upper end of a bar 40 pivoted at its lower end to an operating arm 44 and having a pin 42 arranged to engage the latch bar 26. When the operating arm 44 is so positioned that the roll 36 is resting against the low portion of the cam end 35 of the lever 34 the trip pin 42 holds the latch bar raised so that its end is above a plate 46 secured to the bracket and consequently the auxiliary positioning means 2 is raised out of its active path. Under these conditions the lever 22 is oscillating idly by movement of the arm 25 as the stretching progresses and the pivot 21 constitutes the fulcrum of the lever. When it is desired to put the auxiliary positioning means into action the operating arm 44 is lowered so that the bar 40 is depressed, withdrawing the trip pin 42 on the bar 40 from the latch bar 26, lowering the lever 34 and forcing the upper end of the lever 22 forwardly to position the auxiliary positioning means 2 at the highest point in its active path. At the same time or as soon as the lower end of the lever 22, by rocking on the cam end of the lever 34, has advanced far enough to permit it, the latch bar 26 snaps down in front

of the shoulder formed by the plate 46. The pivotal connection 23 of the latch bar 26 with the lever 22 now becomes the fulcrum and the link 8 receives operative movement 5 to and fro. It is to be noted that further downward movement of the operating arm 44 is without effect on the auxiliary positioning means 2 since the upper portion of the cam end 35 of the lever 34 is concentric 10 with the pivot 32 of the lever. Upward movement of the link 40 will, as soon as the high part of the cam end of the lever 34 has passed from behind the roll 36 and the trip pin 42 bears on the latch bar 26, act 15 to lift the latch bar and permit the spring 38 to re-act and render the auxiliary positioning means inactive.

The operating arm 44 is secured to one 20 end of a rockshaft 50 to the other end of which is secured a second arm 52 having thereon a roll 54 which engages a cam slot 56 formed in a plate 58 which is arranged to be moved up and down through connections to a knee lever 60 which are similar to those 25 described in the British patent above mentioned. Surrounding the shaft 50 is a sleeve 62 which has an arm 64 carrying a roll 66 arranged to engage the upper portion of a slot 68 in the plate 58. On the sleeve 62 is 30 an arm 70 connected by a link 72 to an eccentric positioning means 74 for varying the position of the gripper 3, this mechanism being similar to that disclosed in the British patent above mentioned.

Below the rockshaft 50 is another rock- 35 shaft 76 having thereon an arm 78 carrying a roll 80 which engages a lower portion of the slot 68. On the opposite end of the rockshaft 76 is an arm 82 connected to a stop 84 by which the pulling movement of 40 the gripper 3 is controlled substantially as explained in the patent last above mentioned.

The relative forms and disposition of the 45 two cam slots 56, 68 in the plate 58 and of the three rolls 54, 66, 80 engaging the slots is such that lowering of the plate from its highest position by movement of the knee lever from its extreme position at the right 50 toward the left causes the inclined portion of the slot 68 at its lower end to act on the roll 80 and, through the lever 82, to move the gripper stop 84 forwardly to limit the pulling movement of the gripper. At the 55 same time the uppermost inclined portion of the slot 68 acts upon the roll 66 to rock the sleeve 62 and, through the arm 70 and link 72, to turn the eccentric positioning device 74 so that the gripper is moved bodily 60 toward the shoe. This adjustment, which gives the gripper a short range of pulling movement close to the shoe, is that desired when lasting and sewing the shank portion 65 of the shoe, and as soon as it has been effected the operator begins to feel the re-

sistance to further movement of the knee lever due to a spring plunger 86 with which the knee lever comes into engagement.

When the operation has progressed far enough toward the forepart of the shoe so 70 that the auxiliary positioning means 2 is required for use the operator continues the movement of the knee lever, causing the plate 58 to descend further. At this time, however, the roll 66 which controls the eccentric positioning device 74 is in the upper vertical portion of the cam slot 68 and the roll 80 which controls the gripper stop 84 is in an intermediate vertical portion 80 which lies between two inclines of the lower portion of the slot 68. For a time, therefore, the gripper is unaffected by movement of the plate 58. At this time, however, the roll 54 on the arm 52 enters and traverses a part of the inclined portion of the slot 56, causing the arm 44 to move the link 40 downwardly and set the auxiliary positioning means into action by releasing the latch 26 and depressing the cammed end of the lever 35. This having been effected, the roll 80 of the gripper stop reaches the end of the vertical portion 90 of the slot 68 and enters the upper incline which acts on the roll 80 to move the stop 84 away from the gripper, enabling the operator, by further movement of the plate, to increase at will the pulling action of the gripper without affecting the other adjustments of the machine, it being observed that the auxiliary positioning means is uninfluenced by movements of the lever 34 due to lowering of the plate 58 to a position lower than that required just to bring the high part of the cam end 35 of the lever 34 into action.

Having thus described our invention, what we claim as new and desire to secure by Letters Patent of the United States is:

1. In a machine for operating progressively upon a shoe through successive cycles, auxiliary positioning means arranged for movement into and out of operative position, means for actuating the auxiliary positioning means when in operative position toward and from the shoe in each cycle, and means under control of the operator during operation of the machine for moving the auxiliary positioning means to its inoperative position and beyond the path of its movement when in operative position.

2. In a machine for operating progressively upon a shoe through successive cycles, auxiliary positioning means arranged for movement into and out of operative position, means for actuating the auxiliary positioning means when in operative position toward and from the shoe in each cycle, and means for moving the auxiliary positioning means out of operative position a distance substantially more than the distance through which it moves when in operative position.

3. In a machine for inserting fastenings through the edge extension of a shoe, the combination of auxiliary positioning means movable into and out of operative position, 5 means for operating the auxiliary positioning means when in operative position through a short path to permit the shoe to be fed when operating upon the forepart and to prevent substantial tipping of the 10 shoe, and means operable when operating on the shank to move the said positioning means to its inoperative position and beyond its path of operative movement to enable the shoe to be tipped.
- 15 4. In a machine for sewing through the edge extension of a shoe, the combination of positioning means arranged to engage the shoe bottom when sewing one part of the shoe and prevent tipping of the shoe to cause the stitches to be inserted substantially perpendicularly to the edge extension, means for effecting a slight operative movement of the positioning means in each 20 cycle to permit feeding of the shoe, and means operable when sewing another part of the shoe to move the positioning means out of operative position to permit tipping of the shoe to cause the stitches to be inserted at an oblique inclination to the edge 25 extension.
- 30 5. In a machine of the class described, a positioning device arranged to engage the shoe bottom, means for effecting a predetermined operative movement of said device toward and from the shoe, and means arranged between the device and its operating means manually operable when the machine is in operation to vary the position of said device relatively to its operating means, the 35 extent of its operating movement remaining unchanged.
- 40 6. In a machine of the class described, a positioning device arranged to engage the shoe bottom, means for effecting a predetermined operative movement of said device toward and from the shoe, and means comprising an eccentric and a hand lever for varying the position of said device relatively to the shoe without altering the extent of its 45 operative movement.
- 50 7. In a machine of the class described, a positioning device arranged to engage the shoe bottom, means for effecting an operative movement of said device toward and from the shoe, and means for varying the position of said device relatively to the shoe in the direction of its operative movement while the extent of its operative movement 55 remains unchanged including a hand lever and means for audibly indicating to the operator the amount the lever is turned in either direction when the position of said device is changed.
- 60 8. In a machine of the class described, a positioning device arranged to engage the 65 shoe bottom, means for effecting an operative movement of said device toward and from the shoe, and means for varying the position of said device relatively to the shoe while the extent of its operative movement 70 remains unchanged comprising an eccentric, a hand lever connected thereto and means for audibly indicating to the operator the amount the eccentric is turned.
9. In a machine for lasting and sewing 75 stitchdown shoes, the combination of positioning means for a shoe, a gripper, auxiliary positioning means arranged over the shoe bottom and movable when in operative position to permit feeding movements of the shoe and movable out of operative position to permit tipping of the shoe, means for controlling operation of the gripper, and a unitary means for effecting during operation of the machine movement of the auxiliary positioning means into and out of operative position and movement of said gripper controlling means.
10. In a machine for lasting and sewing 80 stitchdown shoes, the combination of positioning means for a shoe, a gripper, auxiliary positioning means arranged over the shoe bottom and movable when in operative position to permit feeding movements of the shoe and movable out of operative position 85 to permit tipping of the shoe, means for controlling operation of the gripper, and a unitary means for effecting during operation of the machine movement of the auxiliary positioning means into and out of operative position and movement of said gripper controlling means.
11. In a machine for lasting and sewing 90 stitchdown shoes, the combination of positioning means for a shoe, a gripper, auxiliary positioning means arranged over the shoe bottom and movable when in operative position to permit feeding movements of the shoe and movable out of operative position 95 to permit tipping of the shoe, means for controlling operation of the gripper, and a single member movable by the operator first to render the gripper active, then to render the auxiliary positioning means active and then to control the amount of gripper action in excess of that existing prior to the coming into action of the auxiliary positioning means.
12. In a machine for lasting and sewing 100 stitchdown shoes, the combination of sewing instrumentalities, a lasting gripper, positioning means, means for varying the pulling movement of the gripper, auxiliary positioning means movable into and out of operative position, means for varying the initial position of the gripper, and means for varying the pulling movement of the gripper.
13. In a machine of the class described, 105 the combination of means for operating 110
14. In a machine for lasting and sewing 115 stitchdown shoes, the combination of sewing instrumentalities, a lasting gripper, positioning means, means for varying the pulling movement of the gripper, auxiliary positioning means movable into and out of operative position, means for varying the initial position of the gripper, and means for varying the pulling movement of the gripper, and means under the operator's control 120 for simultaneously effecting the gripper adjustments and subsequently effecting movement of the auxiliary positioning means into operative position.
15. In a machine of the class described, 125 the combination of means for operating 130

progressively about the periphery of a shoe, a device arranged to engage the shoe, a lever having connection to said device, power means for oscillating the lever, a knee control, and connections from said knee control to said lever to cause the said device first to be moved into operative position and then to provide an effective fulcrum for the lever to cause said device to be operated toward

10 and from the shoe.

14. In a machine of the class described, the combination of means for operating progressively about the periphery of a shoe including an upper pulling gripper, a positioning device arranged to engage the shoe, a power operated lever having connection to said device, a knee control, and connections from said knee control to said lever and to the gripper to cause the positioning

15 20 device first to be moved into operative posi-

tion, then to be operated toward and from the shoe and then to vary the pulling action of the gripper.

15. In a machine of the class described, the combination of means for operating 25 progressively about the periphery of a shoe including an upper pulling gripper, a device arranged to engage the shoe, power means for operating the device, a knee lever, a slotted plate movable by the knee lever, and connections from said plate to said device to cause movement of the plate first to move the device into operative position, then to cause the device to be operated toward and from the shoe and then to effect adjustment 30 35 of the gripper.

In testimony whereof we have signed our names to this specification.

FRED RICKS.

REGINALD BOYD WOODCOCK.
